UNITED STATES PATENT OFFICE

JOHN A. LAWSON, OF NEW YORK, N. Y.

STARTING-CRANK FOR INTERNAL-COMBUSTION ENGINES.

938,254.

Specification of Letters Patent.

Patented Oct. 26, 1909.

Application filed February 26, 1909. Serial No. 480,137.

To all whom it may concern:

Be it known that I, JOHN A. LAWSON, a citizen of the United States, and a resident of the city of New York, borough of Brooklyn, in the county of Kings and State of New York, have invented a new and Improved Starting-Crank for Internal-Combustion Engines, of which the following is a full, clear, and exact description.

10 This invention relates to certain improvements in starting cranks for internal combustion engines, and more particularly to an improved means whereby the crank may be locked to the shaft by the mere act of 15 grasping the handle of the crank, and whereby the releasing of the handle will release the grip of the crank upon the shaft.

In my improved starting crank I employ two opposed gripping members for engagement with opposite sides of the shaft, and both of these members are connected to crank arm members which have a relative longitudinal movement. At the outer ends of the crank arm members are two handle 25 members, so constructed and connected to the crank arm members that the act of grasping the handle will force the gripping members toward each other to engage with the shaft.

30 Reference is to be had to the accompanying drawings, forming a part of this specification, in which similar characters of reference indicate corresponding parts in all the figures, and in which—

35 Figure 1 is a perspective view of a starting crank constructed in accordance with my invention; Fig. 2 is a side elevation, a portion being shown in longitudinal section; Fig. 3 is a side elevation, the handle being shown in 40 folded position; and Fig. 4 is an end view of the gripping portion of the crank, the shaft being shown in transverse section.

In the specific form of my improved device illustrated in the accompanying drawings, I provide two gripping members 10 and 11, each substantially cylindrical in form and having curved opposite faces for receiving therebetween the shaft 12 of an internal combustion engine. The outer member 10 is provided with outwardly-extending flanges 13, to which are bolted outwardly-extending flanges 14 of a curved shell or casing 15. The shell or casing 15 is of somewhat larger diameter than the gripping member 10, and its inner surface is curved to fit the exterior surface of the gripping

member 11. The gripping member 11 is enclosed within the casing or shell 15 and is movable in respect thereto toward and from the member 10. The members 10 and 11 are of such size that the shaft may freely rotate between the two when they are separated, but when the members are forced toward each other the shaft is firmly gripped therebetween. The casing member 15 is formed integral with, or at least rigid with, a crank arm member 16, extending outward radially in respect to the shaft, the gripping member 11 being formed integral with, or at least rigid with, a crank arm member 17 extending outwardly parallel to the crank arm member 16. The crank arm member 16 is preferably substantially U-shaped in cross section and the member 17 is disposed within the groove or channel of the member 16, so as to be partially concealed and protected thereby. The casing 15 is provided with an aperture in alignment with the end of the groove or channel in the member 16 and through this aperture the arm 17 extends to the outer surface of the gripping member 11. Thus, a relative longitudinal movement of the two crank arm members 16 and 17 forces the two gripping members 10 and 11 toward or from each other.

The two gripping members are normally spread apart to their limiting position so as to automatically free themselves from the shaft, and for accomplishing this any suitable form of spring mechanism may be employed. As illustrated, the crank arm member 17 is provided with a collar 18 intermediate its ends, which engages with a shoulder 19 in the groove, and a coil spring 20 encircles the crank arm member 17 and extends from the collar 18 to a transverse pin 21 in the crank arm member 17. The spring tends to spread the collar and the pin apart, and as the collar is movable in respect to the member 17 but held against movement in respect to the member 16, it is evident that the spring will tend to draw the gripping member 11 into engagement with the casing wall and away from the member 10, as illustrated in Fig. 1.

At the outer end of the crank arm members 16 and 17 are two handle members 22 and 23, relatively movable to effect a relative movement of the crank arm members 16 and 17. These handle members may be connected to the crank arm members in various different ways, but for convenience in stor-

ing the crank when it is detached from the shaft, I preferably so connect them that the handle may occupy a position substantially parallel to the crank arm. In the specific 5 form illustrated, the handle member 22 is substantially channel-shaped in cross section and is provided with outwardly-extending lugs 24 pivoted to the side of the member 16. The handle member 22 may swing outwardly 10 to a position at right angles to the crank arm member, but further outward movement is prevented by the engagement of the end of the handle with the side of the crank arm. For locking the handle member 22 in 15 this position, it may be provided with a lug 25 adjacent its hinged end and adapted for engagement with a spring 26 carried by the side of the crank arm member 16. The spring may be rigidly secured to the crank 20 arm member at one end and may have the other end free to move out of the path of the lug 25 to permit the passage of the latter. With the handle at right angles to the crank arm, the spring snaps behind the 25 lug and holds the handle in position. The second handle member 23 is secured to the handle member 22 by a pivot pin 27 disposed intermediate the ends of the handle, and the handle member 23 is so disposed 30 that it may lie within the groove or channel of the member 22. One end 28 of the handle member 23 extends beyond the hinge end of the member 22 and extends through an opening in the side of the crank arm member 16 when the handle is at right angles to the crank arm. This terminal portion 28 comes into engagement with the outer end of the crank arm member 17, as shown particularly in Fig. 1, so that by forcing the 35 handle members 22 and 23 toward each other, the extension 28 will serve to force the crank arm member 17 longitudinally in respect to the crank arm member 16, and effect the gripping of the shaft between the members 40 45 10 and 11.

In using my improved starting crank, the two gripping members 10 and 11 are brought into operative engagement with the shaft and the handle member 22 is locked in position at right angles to the crank arm member 16. The two handle members 22 and 23 are then forced toward each other to grip the shaft and the crank is then used to turn the shaft in the ordinary manner. The instant the engine starts or in case of back-fire, the operator immediately releases the handle and the spring separates the gripping members, so that the shaft may freely turn in either direction independently of the crank. 50 Even should the crank be jerked out of the hand of the operator, the instant that the handle is free the crank will become released so as to prevent damage by the rapidly moving crank.

Having thus described my invention I 65 claim as new and desire to secure by Letters Patent:

1. A starting crank for internal combustion engines, comprising two members having opposed gripping surfaces for receiving therebetween the engine shaft, two crank arm members having relative longitudinal movement and connected to the first-mentioned members respectively, a handle member pivotally connected to one of said crank arm members and movable to a position at right angles thereto or to a position substantially parallel thereto, and a second handle member pivotally connected to the first-mentioned handle member and having operative engagement with the other crank arm member when said handle members are at substantially right angles to the crank arm members. 80

2. A starting crank for internal combustion engines, comprising two members having opposed gripping surfaces for receiving therebetween the engine shaft, a channel-shaped crank arm member secured to one of said first-mentioned members, a second crank arm member connected to the other of said first-mentioned members and disposed within the channel of the first-mentioned crank arm member, a spring within said channel and normally tending to move said gripping surfaces away from each other, and handle members pivotally connected together and in operative engagement with the outer ends of said crank arm members, the handle member connected to the channel-shaped crank arm member also being channel-shaped and adapted to receive the other handle member. 95

3. A starting crank for internal combustion engines, comprising two members having opposed curved gripping surfaces for receiving therebetween the engine shaft but unattached to the latter, two crank arm members having relative longitudinal movement and connected to said first-mentioned members respectively, a channel-shaped handle member pivotally connected to one of said crank arm members and movable to a position at right angles thereto or to a position substantially parallel thereto, and a second handle member pivotally connected to the first-mentioned handle member and normally disposed within the groove thereof and having operative engagement with the other crank arm member when said handle members are at substantially right angles to the crank arm members. 110

In testimony whereof I have signed my name to this specification in the presence of two subscribing witnesses.

JOHN A. LAWSON.
